per A. B. Upham,
His Attorney.

UNITED STATES PATENT OFFICE.

GEORGE D. BAIRD, OF PEORIA, ILLINOIS, ASSIGNOR OF TWO-THIRDS TO
CHARLES A. TAYLOR AND WILLIAM E. LITTLEFIELD, BOTH OF SAME
PLACE.

GRAIN-WEIGHER.

SPECIFICATION forming part of Letters Patent No. 355,248, dated December 28, 1886.

Application filed June 1, 1885. Serial No. 167,335. (No model.)

To all whom it may concern:

Be it known that I, GEORGE D. BAIRD, of Peoria, in the county of Peoria, in the State of Illinois, have invented an Improved Grain-
5 Weigher; and I do hereby declare that the following is a full, clear, and exact description thereof, reference being had to the annexed drawings, making a part of this specification, in which like letters of reference refer to like
10 parts, and in which—

Figure 1 represents a side elevation of the weigher; Fig. 2, a plan view of the same; Fig. 3, a vertical section at XX in Fig. 2; Fig. 4, a perspective view of the fans of the weigher; Fig. 5, a sectional view showing the fan-lock; Fig. 6, a vertical section of the elevator and of the hood-spout for delivering the grain from said elevator to the weighing device; Fig. 7, a view of the bucket with a modified form of lock; Fig. 8, a front elevation of the metal plate to which the hood is secured.

The object of this invention is the construction of a machine for automatically weighing grain as delivered thereto in a steady stream. The particular class in which is my invention
25 is that wherein the weighing-bucket is supported by steelyards whose deflection, caused by the mass of grain accumulating in the said bucket, permits said bucket to suddenly empty itself and become ready for refilling.

My invention relates especially to an improved form and construction of the weighing-bucket, which shall not only be simpler in detail, but more sure and efficient in its working. My bucket consists, essentially, of a quadrant-cylinder provided with radial fans adapted to be easily revolved therein, and of a lock arranged to hold said fans rigid within the bucket and release the same when the said
35 bucket is depressed.

In the drawings, B is the bucket; F, the radial fans; S, the steelyards supporting said bucket; E, the elevator, and H, the hooded spout for delivering the grain from the elevator to the bucket.

The bucket B consists simply of the two sectors or quadrants B², fixed at the suitable distance apart by the curved side B'. At the corners of the quadrant sides B², opposite to the curved side B', and concentric with said latter side, are bearings for the shaft or axis

A, which supports the fans F. Said axis I usually form of metal cast into the requisite shape and provided with the projections A', to which to secure the fans F. Said fans may 55 be made of wood; but I prefer to make them of sheet metal, and to form each fan in two parts, one of which is radially movable upon the other, for the reasons hereinafter described. The one part, F', is fastened rigidly 60 to the axis A, and is provided with the lateral folded edges F³, in the grooves formed by which the other fan part, F², can easily slide. To prevent said part F² from dropping entirely out from its holding-grooves, the inner corners 65 of said part F² are bent up somewhat and the outer portion of the doubled edges F³ are bent down somewhat closer, so as to form stops.

The steelyards consist of the slotted shank S and the two arms S', to the ends of which 7c the bucket B is pivotally fastened, having such pivotal points above the center of gravity of said bucket. The weight W is held to the steelyards S by the bolt W', passing from said weight up through the slot S² to the nut W², 75 held from turning by the cup U, fitting about said nut and having ears U' projecting into said slot S². By turning the weight W tightly up against the steelyard-shank it is held thereby immovably wherever set. By unscrewing said 80 weight it is unloosened and can be moved along to a new point of adjustment. To cause the bucket B to drop instantly and quickly as soon as the inflowing grain overbalances the weight W, I lower the fulcrum center of the steelyards by means of the sub-arms T, rigidly depending from the steelyard-arms S'. At the end of each of said sub-arms are two or more pin-holes to receive the bearing-pins, held by suitable supports. I make the extra pin-holes 85 90 to permit of adjustment of said bearing-pins to and from the steelyards, so as to vary the quickness of tripping of the weigher.

The elevator E is adapted to support the weigher by means of a bearing-pin, P, entering 95 corresponding pin-holes in each sub-arm T, said pins being held one by the branch R' of the bar R projecting from the elevator E, and the other projecting directly from the elevator itself. As each fan F passes down 100 into the bucket B by the revolution of the whole, it is brought to a stop at the vertical

edge of said bucket by coming in contact with the lip L' of the latch L, pivoted to the side of the bucket. To release such fan and permit it to pass onward and the grain held thereby to escape, the tail of said latch comes against the pin L³, projecting from the elevator, as the bucket descends, its grain having overbalanced the weight, and the lip L' is depressed until below the lower edge of the fan F and the latter is loosened therefrom.

In constructing the hooded spout H, I substitute the metal plate K, having the notch K' in the upper edge thereof, for a portion of the ordinary wooden side. At the bottom of said plate is the lug or lip K², having a bolt-hole through it. Into said notch the lower part of said hood is bent, and secured therein by passing a bolt through the lower corners of said hood and said bolt-hole. The upper part of said hood is tacked to the edges of the elevator. The object of this wedge shape of the spout is that it may be as little as possible in the way of the fans as they pass on down into the bucket. To make the delivery end of said spout as wide as possible without danger of its being struck by the fans is the reason why I make said fans longitudinally contractible, as previously described. As the fans revolve above the axis A, gravity causes the movable part F² to slide toward the center, and, thus shortened, their outer edges can safely pass the spout H. As each fan passes on down into the bucket, gravity again actuating said said movable part, elongates the same and brings the outer edge thereof against the curved side B', making a better fit thereagainst and less liable to binding than if the fans were solid.

Instead of locking the fans F by the direct engagement therewith of the latch L, I may rigidly fix a notched disk, A², to the projecting end of the axis A, and with which said notched disk said latch is adapted to engage and to be released therefrom as in the other way.

What I claim as my invention, and for which I desire Letters Patent, is as follows, to wit:

1. The combination, with the slotted steel-yards and the bucket supported thereby, of the weight W, having the bolt projecting rig-

idly therefrom through the slot S² of said steel-yards, the nut for said bolt and the cup U, fitting about said nut and having ears U', projecting into said slot, substantially as and for for the purpose specified. 50

2. In a grain-weigher, the horizontally-fixed bar R, having the branch R' and the stop-arm R³, the bifurcated steelyards S, having one fulcrum-bearing on said branch and the other in the support of said bar, and the weight W, in combination with the quadrant sides B² and the curved side B', forming the bucket B, the 60 radial fans F, mounted in said bucket, and the latch L, substantially as and for the purpose set forth.

3. In a grain-weigher, the combination, with the bucket formed with the two plane parallel 65 sides and the quarto-cylindrical side, of the axis A, mounted in said bucket coincident with said curved side, and the fans F, projecting from said axis and having the outer portion of each separate and radially movable, substantially as and for the purposes specified. 70

4. In fans for a grain-weigher of the kind herein set forth, the axis A, having the projections A', in combination with the fan parts F', secured to said projections and having the 75 doubled lateral edges F³, and the fan parts F², adapted to be easily slid in the grooves formed by said doubled edges, substantially as and for the purpose set forth.

5. In a grain-weigher, the combination, with 80 the steelyards having suitable fulcrum-bearings, the bucket B, supported by said steelyards, and the radial fans F, adapted to be revolved in said bucket, of the latch L, pivoted to said bucket and having the lip L', by which 85 said fans are individually held in said bucket, and a stop adapted to elevate the tail of said latch when the bucket is depressed and thereby release said fans from the lip L', as set forth.

In testimony that I claim the foregoing as 90 my invention I have hereunto set my hand this 12th day of May, 1885.

GEORGE D. BAIRD.

In presence of—

A. B. UPHAM,
A. KEITHLEY.
